US00D923428S

(12) **United States Design Patent** (10) **Patent No.:** **US D923,428 S**
(45) **Date of Patent:** **** Jun. 29, 2021**

(54) **BOTTLE CONTAINER**

(71) Applicant: **Vinglacé, LLC**, Houston, TX (US)
(72) Inventor: **Colton Bryan Haas**, Houston, TX (US)
(73) Assignee: **Vinglacé, LLC**, Houston, TX (US)

(**) Term: **15 Years**

(21) Appl. No.: **29/748,002**

(22) Filed: **Aug. 26, 2020**

Related U.S. Application Data

(63) Continuation of application No. 16/983,964, filed on Aug. 3, 2020, which is a continuation of application

(57) **CLAIM**

The ornamental design of a bottle container, as shown and described.

DESCRIPTION

FIG. 1 is a front right top perspective view of a bottle container showing my new design;

FIG. 2 is a front right bottom perspective view of the bottle container of FIG. 1;

FIG. 3 is a front elevated view of the bottle container of FIG. 1;

FIG. 4 is a rear elevated view of the bottle container of FIG. 1;

FIG. 5 is a right side elevated view of the bottle container of FIG. 1;

FIG. 6 is a left side elevated view of the bottle container of FIG. 1;

FIG. 7 is a top plan view of the bottle container of FIG. 1; and,

FIG. 8 is a bottom plan view of the bottle container of FIG. 1.

The broken lines in the drawings depict portions of the bottle container that form no part of the claimed design.

1 Claim, 7 Drawing Sheets

Related U.S. Application Data

No. 29/713,086, filed on Nov. 13, 2019, now Pat. No. Des. 892,568, which is a continuation of application No. 16/562,474, filed on Sep. 6, 2019, now Pat. No. 10,703,553, and a continuation of application No. 16/334,793, filed as application No. PCT/US2017/053642 on Sep. 27, 2017, now Pat. No. 10,787,304, which is a continuation of application No. 15/699,462, filed on Sep. 8, 2017, now Pat. No. 9,988,202.
